TELESCOPE MOUNT FOR RIFLE

Fred T. Hansen, 820 Thrush St., Green Bay, Wis.

Filed Oct. 28, 1964, Ser. No. 82,387

Term of patent 14 years

(Cl. D30—1)

Fig.1.

Fig.2.

Fig.3.

FIGURE 1 is a perspective view of a telescope mount for rifle embodying my new design;

FIGURE 2 is a side view thereof; and

FIGURE 3 is a front view thereof.

The dominant features of my design reside in those portions thereof shown in solid lines.

I claim:

The ornamental design for a telescope mount for rifle, as shown and described.
